Primary Examiner — T. Chase Nelson(74) *Attorney, Agent, or Firm* — Kilpatrick Townsend & Stockton LLP**CLAIM**

The ornamental design for a shoe, as shown and described.

DESCRIPTION

FIG. 1 is a front perspective view of an embodiment of a shoe.

FIG. 2 is a rear perspective view of the shoe of FIG. 1.

FIG. 3 is a right side view of the shoe of FIG. 1.

FIG. 4 is a left side view of the shoe of FIG. 1.

FIG. 5 is a rear view of the shoe of FIG. 1.

FIG. 6 is a bottom view of the shoe of FIG. 1; and,

FIG. 7 is a partial view of a portion of a midsole of the shoe of FIG. 1.

The dash-dot broken lines represent an unclaimed boundary of the claimed design. The broken lines immediately adjacent to shaded areas represent unclaimed boundaries of the claimed design. The broken lines that appear over portions of the midsole and outsole regions represent unclaimed portions of a pattern thereon and form no part of the claimed design. The stippled surface shading in the partial view of the portion of the midsole represents the three-dimensional appearance of the claimed portion of the pattern. The stippled surface shading of the claimed portion of the pattern was omitted from the larger views of the shoe for clarity of illustration. The remainder of the shoe shown in broken lines is for environmental purposes only and forms no part of the claimed design.
